UNITED STATES PATENT OFFICE.

HENRY A. WEIHMAN, OF PHILADELPHIA, PENNSYLVANIA, ASSIGNOR TO JOHN F. SIMONS AND THOMAS MADDOCK, OF PHILADELPHIA, PENNSYLVANIA, FREDERICK M. SIMONS, OF SWARTHMORE, PENNSYLVANIA, AND EDWIN S. SIMONS, OF ORANGE, NEW JERSEY, TRADING AS SIMONS BROTHERS & COMPANY, OF PHILADELPHIA, PENNSYLVANIA.

DESIGN FOR A BACK FOR HAND-MIRRORS OR SIMILAR ARTICLES.

SPECIFICATION forming part of Design No. 36,108, dated October 14, 1902.

Application filed July 30, 1902. Serial No. 117,733. Term of patent 8½ years.

To all whom it may concern:

Be it known that I, HENRY A. WEIHMAN, a citizen of the United States, residing at Philadelphia, in the county of Philadelphia and State of Pennsylvania, have invented and produced a new and original ornamental Design for a Back for Hand-Mirrors or Similar Articles, of which the following is a specification.

In the drawing the design is shown applied to an article of a toilet-set, such as a brush or hand-mirror.

As shown in the drawing, the leading feature of my design consists of a body part A, ornamented with the bust portion of a figure of a nymph f, having outstretched arms and surrounded by raised or embossed portions b, representing lilies and their leaves, and parts d, representing strand or ribbon effects gracefully entwined with the lilies.

At the center below the bust of the nymph and between the outstretched arms is a shield effect e. The body portion is elliptical, and the

handle portion B extends in the direction of its longest axis and is somewhat enlarged at its free end C. This handle is also ornamented by lily effect c c and ribbon effects d i, the ribbon effect d being a continuation of the effect from the body portion A, as shown. The lower part C of the handle is also provided with a smooth surface h within the ribbon effects d.

Having now described my invention, what I claim as new, and desire to secure by Letters Patent, is—

The ornamental design for back of hand-mirror or similar article, as herein shown and described.

In testimony of which invention I have hereunto set my hand.

HENRY A. WEIHMAN.
